UNITED STATES PATENT OFFICE

HAROLD D. WELLS, OF GLENS FALLS, NEW YORK

PULP SCREEN

Application filed December 7, 1929. Serial No. 412,525.

This invention is designed to provide a pulp screen for handling a wide variety of pulp, such as paper stock, sulphite pulp, soda pulp, sulphate pulp, groundwood pulp, and defibered waste paper. It is further designed to produce finer quality pulp than other screens, by combining inward flow screening and centrifugal separation. This action is further accomplished by a gentle screening action, while at the same time, the paper making fibre is removed from the stock and none of it left in the tailings which are rejected and discharged.

Objects of the invention are to provide a screen which passes only the best quality paper making fibre and thoroughly cleans the stock; to provide a completely enclosed screening apparatus preventing the entrance of foreign matter into the stock and over-coming any danger of spilling during the screening operation; to provide an apparatus in which no air is mixed with the stock in the screen, in which there is no foaming and in which no lumps are formed; to provide a screen requiring no concrete or other platform and one which may be installed directly upon the main floor of a factory and may discharge at any desired point above the machine proper; to provide a screen in which the motion is entirely rotary, one in which no fresh water is needed, one embodying no shower pipes with consequent danger of clogging, one of continuous operation and embodying no revolving plates, and one of extremely simple, practical construction which will be rugged and efficient and well suited to the requirements of economical operation, convenient manipulation and ready accessibility for repair purposes.

With the foregoing and minor objects in view, the invention resides in the novel subject matter hereinafter described and claimed, description being accomplished by reference to the accompanying drawings.

Fig. 1 is substantially a central vertical longitudinal sectional view through a pulp screen constructed in accordance with my invention.

Fig. 2 is a vertical transverse sectional view on line 2-2 of Fig. 1.

A cylindrical casing 3 is provided, embodying one end wall 4, a second end wall 5, and a continuous side wall formed of sections. Both end walls 4 and 5 are preferably in the form of castings, provided with suitable supporting feet 6. End wall 4 is provided with a volute pulp inlet 7 communicating by means of a slot 8 with the interior of the cylinder 3 and serving to swirl the pulp as it enters the cylinder, said inlet 7 being provided with a flange 9 instrumental in attaching a steam pipe or the like thereto. The end wall 5 is provided with a screened pulp outlet opening 10 whose peripheral edge is spaced inwardly from the casing side wall, said opening 10 being in communication with an external passage 11 which is flanged at 12 for connection with a conducting line for the screened pulp. In the present showing, the passage 11 is provided with a clean-out 13 and with a drain 14.

The side wall of the casing 3 embodies a lower longitudinal plate 15, an upper longitudinal plate 16, both of these plates being flanged and secured by cap screws or the like 17 to the end walls 4 and 5, and two arcuate sheet metal side wall sections 18 secured to the plates 15 and 16, by bolts or the like 19. Plate 15 is provided with an opening 20 which may if desired be provided with a valve plate or the like 21 having any desired operating means not shown. This opening 20 may either constitute a tailings outlet or a clean-out, as may be desired. The top plate 16 is provided with a tailings outlet 22 which is preferably provided with a lip 23 to intercept the swirling tailings and direct them through said outlet.

Within and concentric with the cylinder 3, is a cylindrical openwork screen frame 24 which embodies a closed end 25, an open end provided with a ring 26 of T-shape in transverse section, and a side wall portion which consists of longitudinal bars 27 integral with rings 28, the ends of said bars being integral with the closure 25 and the ring 26 respectively. A portion of this ring is snugly received in the opening 10 and its outstanding flange is secured by cap screws or the like 29 to the end wall 5. Secured to the outer side of the

frame 24 and forming therewith a cylindrical pulp screen, are a number of arcuate screen plates 30 which may be secured to said frame by screws or in other desired ways.

5 The closed end 25 of the pulp screen frame, is inwardly spaced from the end wall 4 of the casing 3, and a scraper driving disk 31 is rotatably mounted in the space between said parts 25 and 4. Annular scraping means is 10 secured to the disk 31 and surrounds the pulp screen. In the present showing, this scraping means embodies a plurality of scraper bars or blades 32 extending longitudinally of the screen side wall and disposed at the exterior 15 of the latter, said bars or blades being joined at one end to a ring 33, at their other ends to a ring 34, and between their ends to a plurality of rings 35. Ring 34 is secured by cap screws or the like 36 to the disk 31. The other 20 rings 33 and 35 surround the screen and the ring 33 is disposed against the peripheral flange of the ring 26 above described. This ring 33 is preferably provided with a lining 37 of soft rubber which contacts with the 25 screen plates 30 and serves as an effective, anti-vibratory bearing for the end of the annular spacing means remote from the disk 31. This annular scraping means, if desired, may be circumferentially divided into sections.

30 For illustrative purposes, each of the rings 33, 34 and 35 is shown divided into two sections, and releasable connections 38 and 39 are shown between said sections of the rings 33 and 35 respectively, no such connections 35 being needed between the sections of the ring 34 in view of the fact that these sections are secured directly to the disk 31. It may be explained that the connections 38 and 39 are merely shown for illustrative purposes and 40 that any other desired connecting means could be employed instead.

Removal of either side wall section 18 gives access to the annular screen scraping means so that the sections of the latter may 45 be disconnected from each other and disconnected from the disk 31, allowing said sections to readily be removed, for instance, when repairs are necessary. When the entire scraping means is thus removed, the ring 50 26 may be disconnected from the end wall 5 and the entire screen and its frame 24 may be removed for repairs or for any other reason.

Any appropriate means may be provided 55 for mounting and driving the disk 31. In the present showing, this disk is provided with an outwardly projecting hub 40 which is keyed at 41 upon a longitudinal shaft 42, said hub being within a stuffing box 43 with which 60 the end wall 4 is provided. Shaft 42 is disposed at one end of the machine only and is mounted in appropriate bearings 44 carried by a bracket 45 which may well be integral with the end wall 4. A pulley 46 is shown 65 on shaft 42 for driving the same but other

provision may of course be made for this purpose.

In operation, while the screen scraping means 32, etc. is rapidly rotated, the pulp to be screened is introduced through the volute 70 7 which starts the pulp swirling in the direction in which said scraping means is being rotated. The liquid and all sufficiently fine particles of pulp pass through the screen plates 30 to the interior of the screen and are discharged from the machine through the outlet passage 11, while the tailings are discharged at 20, 22, or at both locations. The scraping blades 32 prevent the coarse material from adhering to the periphery of the 80 screen and clogging the latter, and these blades are so pitched that they tend to throw the pulp centrifugally, thus further aiding in keeping the screen clean. Moreover, whenever any blade 32 passes a given point, the 85 liquid pulp which was previously thrown out by said blade, immediately returns toward the screen, so that an oscillatory or reciprocatory motion is constantly given to the liquid in a direction radially of the screen, 90 thereby further aiding in the screening action and assisting in preventing screen clogging.

It will be seen from the foregoing that a rather simple and inexpensive construction has been provided for carrying out the objects 95 of the invention, and while the structure herein disclosed is preferably followed, it is to be understood that within the scope of the invention as claimed, variations may be made.

I claim:

1. A pulp screen comprising a stationary cylindrical casing having a pulp inlet and a tailings outlet, one end wall of said casing being provided with a screened pulp outlet inwardly spaced from the casing side wall, 105 a cylindrical screen having a closed end and an open end, said screen having its side wall inwardly spaced from said casing side wall and having its open end secured to said one end wall of the casing around said screened pulp outlet, the closed end of said screen being inwardly spaced from the other end wall of said casing, a scraper-driving head rotatably mounted in the space between said closed end of said screen and said other end wall of the casing, means for driving said head, and screen scraping means secured to said head and disposed at the exterior of said screen side wall.

2. A pulp screen comprising a stationary 120 cylindrical casing having a pulp inlet and a tailings outlet, one end wall of said casing being provided with a screened pulp outlet inwardly spaced from the casing side wall, a cylindrical screen having a closed end and 125 an open end, said screen having its side wall inwardly spaced from said casing side wall and having its open end secured to said one end wall of the casing around said screened pulp outlet, the closed end of said screen be- 130

- ing inwardly spaced from the other end wall of said casing, a scraper-driving head rotatably mounted in the space between said closed end of said screen and said other end wall of the casing, means for driving said head, screen-scraping blades secured to said head and disposed longitudinally at the exterior of said screen side wall, and annular spacing means connected with said blades and surrounding said screen side wall.
3. A pulp screen comprising a stationary cylindrical casing having a pulp inlet and a tailings outlet, one end wall of said casing being provided with a screened pulp outlet inwardly spaced from the casing side wall, a cylindrical screen having a closed end and an open end, said screen having its side wall inwardly spaced from said casing side wall and having its open end secured to said one end wall of the casing around said screened pulp outlet, the closed end of said screen being inwardly spaced from the other end wall of said casing, a scraper-driving head rotatably mounted in the space between said closed end of said screen and said other end wall of the casing, means for driving said head, screen-scraping blades secured to said head and disposed longitudinally at the exterior of said screen side wall, a ring connecting the ends of said blades adjacent said one end wall of the casing, and an elastic lining for said ring contacting with said screen side wall.
4. A pulp screen comprising a stationary cylindrical casing having a pulp inlet and a tailings outlet, one end wall of said casing being formed with a screened pulp outlet opening whose peripheral edge is inwardly spaced from the casing side wall, an open-work cylindrical screen frame having an open end and a closed end, said frame being inwardly spaced from the casing side wall and having a ring at its open end secured to said one end wall of the casing around said screened pulp outlet, the closed end of said frame being inwardly spaced from the other end wall of said casing, arcuate screen plates secured to said frame and forming therewith a cylindrical pulp screen, a scraper driving head rotatably mounted in the space between the closed end of said screen and said other end wall of the casing, means for driving said disk, and an annular open-work screen-scraping frame surrounding said screen and composed of arcuate sections secured to each other and secured to said disk.
7. In a machine of the type described, the combination of a fixed continuous screen through which the pulp flows inwardly, and centrifugal means rotatable around the screen for effecting pulp separation around said screen.
8. In a machine of the type described, the combination of a fixed continuous screen through which the pulp flows inwardly, and means independent of the screen for pulsating the pulp radially of said screen.
9. A pulp screen comprising a fixed continuous-walled screen, a pulp container around said screen, driven pulp-agitating means at the outer periphery of said screen, and a screened pulp outlet from the interior of said screen.
10. A pulp screen comprising a fixed continuous-walled screen, a pulp container around said screen, rotary pulp agitating means surrounding said screen and mounted for rotation about the screen axis, and a screened pulp outlet from the interior of said screen.
11. A pulp screen comprising a fixed continuous-walled screen, a pulp container around said screen, an annular rotary pulp agitator surrounding and concentric with said screen, and a screened pulp outlet from the interior of said screen.
- In testimony whereof I have hereunto affixed my signature.
- HAROLD D. WELLS.
